UNITED STATES PATENT OFFICE.

WILLIAM H. DYER, OF DOUGLAS TOWNSHIP, MONTGOMERY COUNTY, MICHIGAN, AS-
SIGNOR OF ONE-HALF TO EMMA RAYMOND, OF ENTRICAN, MICHIGAN.

AUTOMOBILE TIMER.

Application filed August 11, 1922. Serial No. 581,250.

To all whom it may concern:

Be it known that I, WILLIAM H. DYER, a citizen of the United States, residing at Douglas Township, in the county of Mont-
5 calm and State of Michigan, have invented a new and useful Improvement in Automobile Timers, of which the following is a specifica-
tion.

My invention relates to timers for timing
10 the ignition of automobiles and similar
vehicles, and while it is more especially in-
tended for Ford cars, and other cars having
a distributor shaft revolving with the
engine, and distributor contacts arranged in
15 a circle about said shaft, it is applicable to
any car employing similar methods of
ignition without departing from my inven-
tion. Its purposes are to make a device that
shall be extremely simple and cheap in con-
20 struction and reliable in operation and that
can be dismounted and separated into its
component parts for cleaning and removing
of worn parts in the easiest possible manner
without the use of any tools, except possibly
25 a wrench.

I attain these purposes by the means
shown in the accompanying drawings in
which Fig. 1 is a vertical section on the line
30 $x-x$ of Fig. 2. Fig. 2 is a section on the
line $y-y$ of Fig. 1. Figs. 3 and 4 are de-
tails to illustrate the method of removal of
the contact member.

Referring to the drawings, 1 is the body
35 of the engine through which passes the dis-
tributor shaft 2. The body 1 is provided
with a seat 3 on which is mounted the dis-
tributor shell 4, containing the contacts 5,
of which there are as many as there are
40 cylinders in the engine. In the present in-
stance, four are shown; but as many as are
desired may be employed according to the
number of cylinders in the engine. The
shell 4 is adapted to revolve on the seat 3
45 for the purpose of advancing or retarding the
spark in the usual manner by means of the
arm 6. This part of the device, however, is
common to many engines and forms no part
of my invention and may be of any desired
50 form or shape according to the engine upon
which it is intended to be used. The same
is true of the contacts 5, which are also of the
usual form and construction, the space be-
tween them being filled with insulation 7.
55 The distributor shaft 2 is also of the regular
form employed on the car upon which the

device is to be used. In this case, the
Ford shaft is shown. The upper end of
the shaft 2 terminates in a slightly reduced
cylindrical portion on which is a collar 8,
held in place by a nut 9. A key 10 passes
60 through the upper end of the shaft 2 and is
retained in position by the collar 8. On
the upper end of the shaft 2 is removably
mounted a hub 12 and a disk 13 secured or
integally formed at its lower extremity. 65
A notch 14 is formed at the upper side
of the cylinder 12, fitting the key 10, thus
compelling the cylinder 12 and disk 13 to
revolve with the shaft 2. An S shaped
70 spring 15 is removably mounted on the out-
side of the hub 12. This spring is so mount-
ed on the hub as to freely oscillate about
it when desired or to be removed from it
by simply sliding off. I effect this purpose
75 by forming the end of the spring into a
nearly complete circle, substantially the
same size as the outside of the hub. The
spring is then bent into an S shape as
shown at 16. An opening 17 is formed in
80 its opposite extremity adapted to receive
the notched extremity 18 of the brush point
end 19. It is evident that when the ex-
tremity 18 is passed through the opening
and turned to the position shown in Fig. 3,
85 the brush point 19 cannot be removed, but
will be held securely in position. But when
turned longitudinally, the brush point can
be easily removed through the opening 17.
The disk 13 is turned upward at one side
90 at a point opposite the opening 17 in the
spring 15 and an opening 20 is formed
in the upturned portion through which the
contact brush 19 passes. The upturned por-
tion is also preferably turned inward as
95 shown in Fig. 1 at 21. While I prefer this
construction, the inturned portion may be
omitted without departing from my inven-
tion and the upturn of the disk 13 should be
of sufficient thickness to serve as a guide
100 for the point 19. The upturned portion may
also be integral with the disk or may be
secured to it in any desired manner. The
shell 4 is retained in position by a spring
22. This also is usual in the construction
105 of automobile engines and forms no part of
my invention.

The operation of my device is as follows:
The shaft 2 revolves with the engine carry-
ing with it the hub 12 and the spring 15.
The brush 19 is kept continually pressed 110

against the inside of the shell, by the spring 15, and as it revolves, comes successively in contact with the contacts 5, thus closing the circuit in the usual manner.

- 5 When it is desired to demount my timer for cleaning or replacing the contact brush 19 or for any other purpose, it is only necessary to remove the spring 22. This releases the shell 4 which can then be lifted off from 10 the seat 3. The nut 9 is then unscrewed, releasing the collar 8, the key 10 withdrawn and the collar 8 can be removed, bringing with it the disk 13 and spring 15, and the spring can then be slipped off the upper extremity of the shaft. The spring 15 is then 15 bent inward until the brush is drawn out of the guide 18 and turned longitudinally with the opening of the spring as already described and the spring itself can be slipped 20 off from the hub 12. The device can thus be completely separated into its component parts without the use of any tools whatever with the exception of a wrench to remove the nut 9 if the device is on the distributor shaft. 25 It will also be noted that, as the brush 19 is pressed inward, the peculiar form of the spring 15 permits it to oscillate on the hub 12 and thus permits the brush 19 to move straight in and out and not at an 30 angle as would be the case if the opposite extremity of the spring 15, where it is mounted on the collar, were not free to oscillate about the collar.

I claim as my invention and desire to 35 secure Letters Patent.

1. The combination in a timer for internal combustion engines, distributing contacts arranged in a circle; a distributor shaft positioned within the circle formed by said contacts and revolving with said engine; a spring removably mounted on said shaft so as to revolve therewith, but free to oscillate thereon, and a contact brush mounted 40 on the outer extremity of said spring and adapted, as said shaft revolves, to engage successively with said contacts.

2. The combination in a timer for internal combustion engines, distributing contacts arranged in a circle; a distributor shaft positioned within the circle formed by said 45

contacts and revolving with said engine; a hub removably mounted on said shaft so as to revolve therewith; a spring removably mounted on said hub so as to revolve therewith, but free to oscillate thereon, and a contact brush mounted on the outer extremity of said spring and adapted, as said shaft revolves, to engage successively with said contacts. 55

3. The combination in a timer for internal 60 combustion engines, distributing contacts arranged in a circle; a distributor shaft positioned within the circle formed by said contacts and revolving with said engine; a hub removably mounted on said shaft so as to 65 revolve therewith, but free to oscillate thereon, and a contact brush removably mounted on the outer extremity of said spring and adapted, as said shaft revolves, to engage successively with said contacts. 70

4. The combination in a timer for internal 75 combustion engines, distributing contacts arranged in a circle; a distributor shaft positioned within the circle formed by said contacts and revolving with said engine; a hub removably mounted on said shaft so as to 80 revolve therewith, a spring removably mounted on said hub so as to revolve therewith, but free to oscillate thereon; a contact brush removably mounted on the outer extremity of said spring and adapted, as said shaft revolves, to engage successively with 85 said contacts and a guide for said contact member. 90

5. The combination in a timer for internal 95 combustion engines; distributing contacts arranged in a circle; a distributor shaft positioned within the circle formed by said contacts and revolving with said engine; a hub removably mounted on said shaft so as to revolve therewith, an S shaped spring removably mounted on said hub so as to 95 revolve therewith, but free to oscillate thereon; a contact brush removably mounted on the outer extremity of said spring and adapted, as said shaft revolves, to engage successively with said contacts, and a guide for said contact member.

WILLIAM H. DYER.
